[57] CLAIM

The ornamental design for a dispensing bottle, substantially
as shown and described.

DESCRIPTION

FIG. 1 is a perspective view of a dispensing bottle
showing my new design;

FIG. 2 is a top view thereof;

FIG. 3 is a side view thereof;

FIG. 4 is an end view thereof; and

FIG. 5 is a bottom view thereof.

The characteristic features of my design reside in the
appearance and configuration of the closure element in
combination with the wedge-shaped container.
